INHALER

Granville G. Westerfield, Indianapolis, Ind.

Application July 20, 1931. Serial No. 551,827

3 Claims. (Cl. 128—200)

My invention relates to containers, especially those adapted to contain volatile medicaments for use in the treatment of colds or other afflictions of the respiratory system, and to be useful in the application of such medicaments.

It is the object of my invention to produce a container for such medicaments which can be conveniently carried about by the user, which will be sealed when not in use, which will not become contaminated by being carried about, and which can readily be re-charged or re-filled with a supply of medicament.

In accomplishing the objects of my invention, I provide a separable tubular container, each end 15 of which is tapered and is provided with a central opening. One of such openings is normally closed by a spring-actuated valve, and I provide a cap which may be used to seal the other opening; and this cap can also be used, by placing it 20 on the valve-end of the container, to open such valve. The container is conveniently charged by inserting therein a cartridge saturated with volatile inhalant or a cartridge of solid volatile inhalant.

25 The accompanying drawing illustrates my invention: Fig. 1 is a plan of my container with the cap on the open end to seal such end; Fig. 2 is a section on the line 2—2 of Fig. 1; and Fig. 3 is a similar section but with the cap placed over 30 the valve-end to hold such valve in open position.

My inhaler may be made of some material 35 impervious to moisture and oil, such as glass, metal, hard rubber, or preferably a phenolic condensation product, such as bakelite. It comprises a tubular body portion 10 fully open at one end, and having the other end tapered and provided with a central restricted opening 11. The fully open end is closed with a hollow plug 12 fitting tightly within such open end and having a slightly less outside diameter than the body 10. The plug 12 also has a tapered end and a central restricted opening; and this opening is normally closed by a ball 13 pressed against the inner end thereof by a spring 14 suitably 45 supported in the plug 12 as by a pin 15. The tapers at both ends of this assembly increase as the ends are approached, and are of the usual very slight angle where they approach the straight sides in order to receive and hold the 50 cap now to be described.

For sealing the restricted opening 11 of the body 10 I provide a cap 20 adapted to fit over the tapered end of the body and to engage it in sealing relation where the taper is thus very 55 slight. This cap can also be used to hold the ball

valve of the hollow plug 12 in open position, and thus allow free passage of air into or out of the container through the restricted opening of the plug 12. For this purpose, the cap 20 carries a pin 21 for projecting through the restricted opening in the plug 12 and holding the ball 14 away from its seat against the inner end of such restricted opening. In order that the cap 20 will not seal the end of the container when it is in a position to open the ball valve, it is provided with 60 openings 23 in its sides. These openings 23 are conveniently placed well toward the open end of the cap, in order that when the cap is used to seal the opening in the body such openings will overlie the sides of the body and be closed thereby; but when the cap is used to open the valve 13, such openings will overlie the plug 12, which is of a less diameter than the body 10 and will therefore communicate with a passage between the surface of such plug and the inner surface of the cap for 65 the flow of gas or air from such openings 23 in the cap to the restricted opening of the plug.

In preparing my container for use, the plug 12 is removed and a supply of medicament inserted. This supply is conveniently in the form of a cartridge 18 of volatile solid medicament or of absorbent material saturated with volatile liquid medicament. The plug may then be replaced, and will normally seal its end of the container. The other end of the container may be sealed by 70 placing thereon the cap 20. When it is desired to use my device as an inhaler, it is only necessary to remove the cap 20 and to place it in position over the plug 12 where its pin 23 will open the valve and permit the passage of air into the 75 container. It is then possible by placing the tapered end of the body 10 in proximity to the user's nose or mouth to inhale the vapors given off by the medicated cartridge.

80 My container is thus very convenient for use, and may be re-charged with medicament whenever necessary. In addition, it is completely sealed when not in use, and thus prevents the escape of any of the vapors from the medicated cartridge. It is also to be noted that the end of 85 the container from which a user inhales the vapors of the medicated cartridge is completely 90 covered by the cap and prevented from being contaminated when the device is not being used.

95 I claim as my invention:

1. A container for volatile inhalants comprising a tubular body having a tapered end provided with an opening, a hollow plug in the other end of said body, a restricted opening in said plug, a 100 valve sealing such restricted opening, and a cap 110

fitting said tapered end in sealing relationship and said plugged end in nonsealing relationship and having means to open said valve when placed over said plugged end.

5 2. A container for volatile inhalants comprising a separable tubular body, openings in its ends, the opening in one end being normally sealed by a valve, and a cap fitting said valved end in non-sealing relationship and fitting the other end in

10 sealing relationship and having means unsealing said valved end when said cap is placed thereon.

3. A container for volatile medicaments comprising a tubular body having a tapered end,

openings in both ends thereof, one of said openings being normally sealed by a valve, said body near the valve end thereof being of reduced diameter, and a cap adapted when placed over the unvalved end of said body to seal said unvalved end, said cap when it is placed over the valved end of the container being adapted to engage the sides of said container beyond said reduced portion and having openings which overlie such reduced portion and a pin then projecting within the said valved opening to open said valve.
